A. B. Chapman
Attorney.

UNITED STATES PATENT OFFICE.

ALBERT S. MOFFAT, OF BELMONT, MASSACHUSETTS, ASSIGNOR TO HARVEY C. WHEELER, OF BOSTON, MASSACHUSETTS.

TOWEL-HOLDER.

1,218,103.

Specification of Letters Patent.

Patented Mar. 6, 1917.

Application filed December 18, 1915. Serial No. 67,527.

To all whom it may concern:

Be it known that I, ALBERT S. MOFFAT, a citizen of the United States, and a resident of Belmont, in the county of Middlesex and 5 Commonwealth of Massachusetts, have invented certain new and useful Improvements in Towel-Holders, of which the following is a full, clear, and exact specification.

The object of this invention is the construction of improved means for supporting 10 a set of towels to permit them to be freely used, and at the same time securely locked against unwarranted removal.

Referring to the drawings forming part 15 of this specification, Figure 1 is a perspective view of the holding means arranged upon brackets. Fig. 2 is a cross section of the towel holding device alone. Fig. 3 is a sectional view showing the method of fastening a bracket to the panel in a manner to insure against unfastening the same. Fig. 4 is a front view of the upper part of a cabinet having my towel holder disposed therein.

As shown in Fig. 1, the towels 1 are clamped 25 between two bars 2 and 3 by means of two thumb screws 4 passing freely through the upper bar 2 and turning in the under bar 3. So long as these screws are kept firmly down upon the upper bar, the towels cannot be removed from between the bars. Thus to lock 30 the thumb screws from being unscrewed, the head 5 of each of them is formed with a hole 7 through which a slender rod 9 is passed, a head 10 at one end of the rod and 35 a padlock 11 engaging a hole 12 in the other end locking the rod against withdrawal and hence the thumb screws against turning. While this is desirable as far as it goes, it still lacks one feature for perfectly adapting 40 the device to general office and factory use where a great many towels are to be collected and replaced by a single concern.

In other words, for one man to unfasten the locking device, turn the thumb screws, 45 raise the bar 2, take out the towels, count out the proper number of clean towels, introduce the same between the bars 2 and 3, turn down the thumb screws, run the rod 9 through the holes and reapply the padlock, 50 would occupy altogether too much of a man's time, not to mention the time of the waiting team.

I have accordingly adapted the holder to be readily removed with its contained soiled 55 towels, so that another holder previously

filled with fresh towels can be quickly put in its place. To this end, the bar 3 is given a trunnion 13 at each extremity, one of which is designed to be introduced endwise into a socket in the left hand bracket 14. 60 The other trunnion is disposed to be dropped easily into a deep seat 15 in the other bracket 16, so that by raising the right hand end of the bar and drawing the other end out from the hole 17, the entire holder is readily removed from the brackets. 65

To fasten the bars against unwarranted removal, the bracket 16 is formed with an upright ear 19 having a considerable number of holes 18 therein of a size to receive the 70 rod 9. Consequently, by passing the rod 9 through the holes in the screw heads and thence through that one of the holes 18 which is nearest in line with the rod when the trunnion is disposed in the seat 15, and 75 then locking the padlock in the rod-end, both the towels are made secure against their removal from between the bars 2, 3 and the entire holder against unwarranted extraction. 80

Consequently, the towels can be counted out and put between bars 2, 3 at the laundry by comparatively inexpensive help, so that all the collector needs to do is to unlock the padlocks, slide the rods 9 partly out, remove 85 the holder with towels and all, and put in another holder with its supply of towels.

In order to have the bars 2, 3 grip the towels more securely, I prefer to have the lower bar 3 made trough-shaped, with the 90 concave side uppermost, in order that the pressure of the upper bar will force the layers of towel in between the edges of the trough and so insure against their being worked out. See Fig. 2. 95

To keep the brackets 14, 16 from being removed and the entire fixture stolen, I use machine screws 20 introduced through the panel or board 21 into the brackets, but not coming entirely through the bracket-member 100 receiving them, as shown in Fig. 3.

In Fig. 4, the reference numeral 22 designates a cabinet having my towel holder fastened therein. The brackets 14, 16 are unnecessary here, but members containing the 105 hole 17 and seat 15 are here shown as fastened to the sides of the cabinet, the member 24 in which is the seat 15 having the upright ear 19 similarly to the bracket 16.

In using these towels, the outermost one 110

after serving its purpose is thrown over the rod 9 and permitted to hang down behind the others, and so on until all have been employed as much as desired and thrown over with the other soiled towels.

What I claim is:

1. A towel holder comprising two bars, thumb screws for clamping said bars together, the head of each screw having a transverse hole through it, a rod adapted to be passed through the holes in both screws, a stationary member having a socket receiving an end of one of said bars, a stationary member having a seat removably receiving the other end of the last-named bar, and means for locking in place the end of said rod above said seat, both to prevent the rod's withdrawal from the screws and the bar from the seat.
2. A towel holder comprising two bars,

thumb screws for clamping the towels between them, the head of each screw having a hole transversely through it, a rod adapted to be passed through both of said holes, a stationary member having a socket receiving 25 an end of one of said bars, a stationary member having a seat receiving the other end of the same bar, an ear rigid with the last-named member having a line of closely disposed holes fitted to receive the rod, and 30 means for locking the rod in one of the last-named holes and also in the holes through the screw heads.

In testimony that I claim the foregoing invention, I have hereunto set my hand this 35 16th day of December, 1915.

ALBERT S. MOFFAT.

Witness:

A. B. UPHAM.
